UNITED STATES PATENT OFFICE.

ALDEN B. BLODGETT, OF LOWELL, MASSACHUSETTS, ASSIGNOR TO CHARLES H. McEVOY, OF SAME PLACE.

TIP FOR ELECTRIC CONDUCTORS.

SPECIFICATION forming part of Letters Patent No. 598,972, dated February 15, 1898.

Application filed December 22, 1896. Serial No. 616,653. (No model.)

To all whom it may concern:

Be it known that I, ALDEN B. BLODGETT, a citizen of the United States, residing at Lowell, in the county of Middlesex and Commonwealth of Massachusetts, have invented a certain new and useful Improvement in Tips for Electric Conductors, of which the following is a specification.

This invention relates to tips for electric conductors, such as are provided with cores of tinsel-covered threads or cores of spiral wire, said cores being covered with flexible coverings, usually braided coverings of textile material; and said invention consists in the devices and combinations hereinafter described and claimed, the object of the invention being to provide an inexpensive and effectual means of permanently securing the tip to the covering and to the core and thereby to hold the covering over the end of the core, and to prevent the tip from being drawn out of electrical contact with the core.

In the accompanying drawings, Figure 1 is a plan of a conducting-cord provided with my improvement, the end of the cord being represented as covered with a shell or ferrule; Fig. 2, a central longitudinal section of the same on the line 2 2 in Fig. 1; Fig. 3, a plan of a part of a conducting-cord provided with my improved tip, the shell or ferrule being omitted and the fastening-wire being wound helically around the end of the conducting-cord; Fig. 4, a central vertical cross-section on the line 4 4 in Fig. 3; Fig. 5, a plan of the tip-wire or needle enlarged.

The conducting-cord A consists of a core a, which may be of tinsel-covered thread or of a helically-wound wire covered with a tubular braided covering of textile material. The core when made of tinsel-covered thread is usually braided into a tubular form to make a perfect electrical connection between all the threads of the core.

The tip-wire or needle B is rounded at b to enable it to be inserted with ease in the hollow core and to prevent its cutting the core when the same is made of tinsel-covered thread, and said tip-wire or needle B is provided with a transverse hole b' to receive the fastening C, which may be of wire or thread, but is preferably of wire. The end b of the

needle B is inserted in the tubular core until the hole b' is well within the end of said core, and said needle is then secured in place by fastening a wire or thread through the outer covering and core and through said hole b'. The wire fastening is then secured against displacement by bending the ends of said fastening which project beyond the covering toward the adjacent end of said covering, as shown in Fig. 2 at c c', or one end portion of said fastening may be so bent, as shown at c in Fig. 4, while the other projecting end portion of said fastening is wound helically about the covering and beyond the adjacent end thereof to the tip-wire, as shown at c² in Figs. 3 and 4, and, if desired, the fastening-wire may be soldered to the tip-wire beyond the covering.

Where both ends of the fastening-wire are merely bent against the sides of the covering a', as shown at c c' in Fig. 2, said ends and the end of said covering are preferably covered by a shell or ferrule D, as shown in Fig. 1, which fits the end of the conducting-cord 75 proper and prevents the ends of the fastening-wire from being bent or displaced, the outer end of the shell fitting the tip-wire and, if desired, being soldered or otherwise fastened thereto.

I claim as my invention—

1. An electric conductor, comprising a conducting-core, a non-conducting covering and a conducting-needle, having a transverse hole, and a fastening passed through said hole to retain said needle in said covering.

2. An electric conductor, comprising a conducting-core, a non-conducting covering and a conducting-needle, having a transverse hole arranged within said covering, and a fastening passed through said covering and hole to retain said needle in said covering.

3. An electric conductor, comprising a conducting-core, a non-conducting covering and a conducting-needle, having a transverse hole 95 arranged within said covering, and a wire passed through said covering and hole, to retain said needle and wire in place.

4. An electric conductor, comprising a conducting-core, a non-conducting covering and a conducting-needle, having a transverse hole 100 arranged within said covering, and a wire

passed through said covering and hole and bent on the outside of said covering, to retain said needle and wire in place.

5. An electric conductor, comprising a conducting-core, a non-conducting covering and a conducting-needle, having a transverse hole arranged within said covering, a wire passed through said covering and hole and bent on the outside of said covering, to retain said

needle and wire in place, and a shell, surrounding said needle and the end of said covering.

In witness whereof I have signed this specification, in the presence of two attesting witnesses, this 28th day of August, A. D. 1896.

ALDEN B. BLODGETT.
